UNITED STATES PATENT OFFICE.

WYATT T. SEBREE, OF CARROLLTON, KENTUCKY, ASSIGNOR OF ONE-SIXTH TO J. FRANCIS JETT, ONE-SIXTH TO HENRY SMITH, ONE-SIXTH TO LEWIS THOMA, ONE-SIXTH TO DAVID M. BRIDGES, AND ONE-SIXTH TO JOSIAH JETT, ALL OF CARROLLTON, KENTUCKY.

RAILWAY-MAIL CATCHER AND DELIVERER.

939,557.

Specification of Letters Patent.

Patented Nov. 9, 1909.

Application filed June 8, 1908, Serial No. 437,347. Renewed April 5, 1909. Serial No. 488,073.

To all whom it may concern:

Be it known that I, WYATT T. SEBREE, a citizen of the United States, residing at Carrollton, in the county of Carroll and State of Kentucky, have invented certain new and useful Improvements in Railway-Mail Catchers and Deliverers; and I do hereby declare the following to be a full, clear, and exact description of the invention, such as will enable others skilled in the art to which it appertains to make and use the same, reference being had to the accompanying drawings and to the figures of reference marked thereon, which form a part of this specification.

This invention relates to new and useful improvements in railway-mail catching and delivering apparatus and the object in view is to generally improve upon and render more efficient the apparatus covered by my former patent No. 884,868 of April 14, 1908.

The invention comprises various details of construction, combinations and arrangements of parts which will be hereinafter fully described and then specifically defined in the appended claims.

I illustrate my invention in the accompanying drawings, in which:

Figure 1 is a perspective view of my apparatus applied to a car and to a stationary catcher, the apparatus being set in readiness for operation. Fig. 2 is a side elevation of a portion of a car to which my improved mail delivery and catching apparatus is applied. Fig. 3 is a sectional view transversely through a portion of the car showing in elevation the mail catching and delivering apparatus. Fig. 4 is a horizontal section longitudinally through a portion of a car showing in top plan view the mail delivering and receiving apparatus. Fig. 5 is a detail view in elevation of the upper portion of the crane upon which the bag is suspended from the ground. Fig. 6 is a detail sectional view of the means for supporting a bag upon the car. Fig. 7 is a detail view of a mail bag supporting apron. Fig. 8 is a detail view showing a movable collar upon which the netting frame is mounted. Fig. 9 is a detail perspective view showing the means for holding the bag upon the arm of the frame, and Fig. 10 is a detail view showing a latch for holding the swinging frame which carries the netting in a closed position adjacent to the door.

Reference now being had to the details of the drawings by numeral, 1 designates the body of a car having a door 2 of any suitable size and fastened to the frame of the door are the plates 3 which are curved to conform to the contour of the frame and have their outer ends 4 projecting at right angles from the car and against which the collars 5 which are mounted upon the shafts 6 are adapted to contact to limit their movements in one direction. It will be noted that there are two of said shafts 6 mounted parallel to each other and both preferably above the transverse center of the middle of the doorway. A frame, preferably of metal and designated by numeral 7 of general rectangular or square outline, has projecting portions 8 apertured to receive a pivotal bar 9 which is mounted in apertures in integral lugs upon the collars 5, thus allowing the frame to swing freely thereon. A netting, designated by numeral 10 and made preferably of linked chains, is mounted upon said frame and forms a downwardly hanging pocket 11 for the reception of the mail bag or other article to be delivered therein. Upon the lower end of said frame is a lug 12 having its lower end contracted as at 13 and forming a pivot upon which a bag supporting finger 14 is mounted. A spring, designated by numeral 15, is mounted upon said lug and its free end is adapted to be positioned adjacent to said finger for the purpose of holding a mail bag upon the latter. A locking shell, designated by numeral 16, telescopes over the lug 12 and is provided with slots 17 in its lower end which are designed to receive the spring 15 and also the finger 14 for the purpose of holding the latter in a fixed position and allowing the finger to swing around into a position opposite to that shown in Fig. 6 of the drawings when it is desired to adjust the apparatus for delivering mails while the train is moving in opposite direction.

Mounted upon the side of the car are the rods 18, one being mounted preferably upon either side of the door and in alignment with each other. Said rods are mounted in the brackets 19 and are held in place by means of nuts 20 upon the threaded ends of

said rods 18. A rod 21 is provided with an eye 22 through which the rod 18 passes, and 23 designates a coiled spring which is mounted upon the rod 18 and is interposed 5 between the eye 22 of the rod 21 and the bracket 20 adjacent to the doorway and in which one end of the rod 18 is mounted. The outer end of the rod 21 is pivotally connected to a pin 24 which is mounted upon a 10 bracket arm 25 carried by the frame 7, the purposes of said rod 21 and the spring 23 being to break the impact of the force of the mail bag as it comes against the netting upon the frame 7 as the train moves rapidly 15 and catches a bag to be delivered to the car.

A bag receiving apron, designated by numeral 26 and shown in detail in Fig. 7 of the drawings, is provided which is made preferably of metal and has its ends down- 20 wardly bent and extending through apertures in the bottom bar 27 of the frame 7, and pins 28 or any other suitable fastening pins are passed through the frame of the apron 26 to hold the latter upon the frame 7.

The apron 26 is preferably of a width equal 25 to the distance between the door of the car and the outer face of the latter so that, when the frame 7 is folded back against the car, the edge of the apron will not interfere or 30 come in contact with the door of the car if the latter is closed. A double-ended catch, designated in the drawings by numeral 29, is mounted upon the outer edge of the frame 7 and is adapted to engage a catch or stop 35 upon the frame of the door for the purpose of holding the frame 7 at its farthest throw toward the car.

A stationary crane 30 is mounted preferably adjacent to a railway track and is adapted 40 to support a frame 31 which carries a netting 32, made preferably of chains or any other metallic material, and forms a pocket similar to the pocket carried by the frame 7 upon the catch and designed to receive a 45 mail bag to be delivered from a moving car. Said frame 31 is pivotally mounted upon bracket arms 33 upon said standard. Referring to Fig. 4 of the drawings will be seen two rods 34, and 35 designates a plat- 50 form which is fastened to the angle iron beam 36 forming a portion of a framework of the receiving station. A coiled spring 37 is mounted upon each of the rods 34, and 38 designates a rod having an eye 39 at one end 55 mounted upon one of the rods 34 and against which one end of the spring 37 is adapted to bear. An apron 40, substantially similar to the apron 26 before described, is fastened to the frame 31 and affords means 60 which may be employed to receive a mail bag in the event of the bag not being thrown by the momentum of the car into the pocket.

To the upper end of the standard 30 is ad- 65 justably mounted a bracket member 41 having slots 42 therein through which the bolts

43 pass and nuts upon said bolts afford means for holding the bracket 41 in different vertically adjusted positions. To the upper end of said bracket is fixed a plate 44 upon which a swivel plate 45 is mounted, a detail 70 view of which construction is shown in Fig. 5 of the drawings, and a pin or other suitable fastening means, designated by numeral 46, is designed to pass through registering apertures in said plates 44 and 45 for the 75 purpose of holding the plate 45 in an ad- justed position. A crane, designated by num- 80 eral 47, is pivotally mounted upon a pin 48 carried by the lugs 49 which project from the plate 45 and lugs 50 also rise from the swiveled plate 45 and are spaced apart and serve as guides through which the crane arm passes. A pin 51 is mounted in the lugs 50 and upon which the crane is adapted to rest when at its lowest limit. Projecting from 85 the pivotal end of said crane is a rod 52 upon which a weight 53 is adjustably held. At the free end of the crane 47 is pivotally mounted a mail supporting finger 54, and 55 designates a spring which is fixed to said 90 finger and is adapted to hold the ring 56 temporarily upon said finger, a cord or rope 57 being connected to the ring 56 and adapt- 95 ed to engage and hold the mail bag 58 to be delivered. By the provision of the swiveled means at the upper end of the standard 30, it will be noted that the crane arm may be 100 reversed or swung in different positions ac- cordingly as it may be desired to adapt the apparatus for delivery of mail from cars moving in different directions.

A suitable platform, designated in the drawings by numeral 59, forms a portion of the receiving station and upon which a per- 105 son may ascend by means of the ladder 60 to the place the mail bag is positioned upon the apparatus to be picked up by a moving train.

The operation of my invention is as fol- 110 lows:—When the apparatus is in readiness for receiving and delivering mail, the parts assume the position shown in Fig. 1 of the drawings, in which the mail bag to be deliv- 115 ered from the car is suspended upon the finger 14 and the bag to be delivered to the car hung upon the crane in the manner shown. As the mail bag suspended from the frame 7 upon the car comes in contact with the chain 32, the impact of the force of the bag coming against the same will open the 120 pocket formed by the netting 32 at the upper end of the frame 31 coming in contact with the ring which supports the mail bag will cause the same to be pushed off the finger 14. As the bag strikes the netting 32, the frame 125 31 will swing upon its pivot and the im- 130 pact of the bag coming forcibly against the netting will be broken by the rod 38 putting the spring 37 under tension. As the spring 37 recoils, it will cause the frame 31 to swing

around toward the platform from which the mail bag may be conveniently removed from the pocket of the netting. As the netting upon the moving car comes in contact with the mail bag suspended from the crane, the finger 54 will be turned upon its pivot and the frame 7 coming in contact with the ring 56 and the cord or rope 57 will release the ring from the finger 54 and the impact of the force of the bag 58 coming in contact with the netting of the frame 7 will cause the pocket in the netting upon the car to open and receive the bag and, through the medium of the rod 18 which is pivotally connected to the swinging edge of the frame 7 and its other end sliding upon the rod 18 upon which the coiled spring 23 is mounted, will cause said spring to be put under tension and, as the frame swings back toward the car, the swinging movement of the frame 7 will be gradually broken and, upon the recoil of the spring 23, the crane 3 carrying the mail bag will swing back into the doorway of the car, the catch upon the swinging edge of the frame 7 automatically engaging a stop or catch upon the door frame of the car, thus holding the netting carrying the mail bag in the doorway.

When it is desired to shift the frame 7 to adapt the apparatus for receiving mail when the car is moving in the opposite direction, the collars carrying the frame may be moved upon the rods 6 in the opposite edge of the doorway and the bar 18 which is shown pivotally connected to the frame in Fig. 1 of the drawings is detached therefrom and a similar bar upon the opposite side of the doorway is pivotally connected at its end to the frame, thus allowing the door to yield under the impact of receiving the bag in the opposite direction and in a similar manner as hereinbefore described. By the provision of the means shown in Fig. 6, the finger 14 supporting the mail bag may be swung around and held in such position by means of the slots in the shell 16.

It will be understood that the frame 31 which is mounted upon the standard 30 may also be adjusted to receive a mail bag coming from a train in the opposite direction by simply detaching the rod 38 in the manner shown in Fig. 4 of the drawings and pivotally connecting a similar rod upon the opposite side of the crane. As the mail bag 58 is caught from the crane, the counter-balanced arm 52 will cause the latter to be thrown in an upright position. When the crane is not in use, it may be swung around away from its normal operative position and held in an adjusted position by means of the swivel connection intermediate the same and the standard upon which it is mounted.

What I claim to be new is:

1. A mail catching and delivering apparatus for railway mail service comprising, in

combination with a car, a frame pivotally mounted thereon, a netting mounted upon said frame, a rod pivoted at one end to said frame and its other end connected yieldingly to the car, and mail bag supporting means upon said frame, as set forth.

2. A mail catching and delivering apparatus for railway mail service comprising, in combination with a car, a frame pivotally mounted thereon, a netting mounted upon said frame, a rod pivoted at one end to said frame, a bar secured to the car, said rod having an eye through which said bar passes and a spring against which said eye bears yieldingly, and means upon the frame for supporting a mail bag, as set forth.

3. A mail catching and delivering apparatus for railway mail service comprising, in combination with a car, a frame pivotally mounted thereon, a netting mounted upon said frame, a rod pivoted at one end to said frame, a bar mounted horizontally upon the outer face of the car, one end of said rod having an eye through which said bar passes, a coiled spring upon said bar and against which said eye is adapted to bear yieldingly, as set forth.

4. A mail catching and delivering apparatus for railway mail service comprising, in combination with a car, a frame pivotally mounted thereon, a netting mounted upon said frame, an apron projecting from said frame, a bar pivoted to the swinging edge of said frame and having yielding connection with the car, as set forth.

5. A mail catching and delivering apparatus for railway mail service comprising, in combination with a car, a frame pivotally mounted thereon, a netting mounted upon said frame, an apron projecting from said frame, a bar pivoted to the swinging edge of said frame, a bar fastened to the side of the car, said rod having an eye through which said bar passes, a spring upon said bar and bearing yieldingly against said eye, and means upon said frame adapted to support a mail bag, as set forth.

6. A mail catching and delivering apparatus for railway mail service comprising, in combination with a car, a frame pivotally mounted thereon, a netting mounted upon said frame, a rod pivoted at one end to said frame and its other end connected yieldingly to the car, mail bag supporting means upon said frame, and mechanism for holding the frame at the limit of its farthest inner throw toward the car, as set forth.

7. A mail catching and delivering apparatus for railway mail service comprising, in combination with a car, a frame pivotally mounted thereon, a netting mounted upon said frame, a rod pivoted at one end to said frame and its other end connected yieldingly to the car, mail bag supporting means upon said frame, and a latch upon said frame.

adapted to engage a catch upon the door, as set forth.

8. A mail catching and delivering apparatus for railway mail service comprising, in combination with a car, a frame pivotally mounted thereon, a netting mounted upon said frame, a rod pivoted at one end to said frame and its other end connected yieldingly to the car, and adjustable mail bag supporting means upon said frame, as set forth.

9. A mail catching and delivering apparatus for railway mail service comprising, in combination with a car, a frame pivotally mounted thereon, a netting mounted upon said frame, a rod pivoted at one end to said frame and its other end connected yieldingly to the car, a finger swivelly mounted upon said frame upon which a mail bag is adapted to be supported, and means for holding said finger in an adjusted position, as set forth.

10. A mail catching and delivering apparatus for railway mail service comprising, in combination with a car, a frame pivotally mounted thereon, a netting mounted upon said frame, a rod pivoted at one end to said frame and its other end connected yieldingly to the car, a finger swivelly mounted upon said frame upon which a mail bag is adapted to be supported, a spring positioned adjacent to said finger and designed to hold the mail bag thereon, a slotted shell upon the frame adapted to engage and hold said finger in an adjusted position, as set forth.

11. A mail catching and delivering apparatus for railway mail service comprising, in combination with a car, a frame pivotally mounted thereon, a netting mounted upon said frame, a rod pivoted at one end to said frame and its other end connected yieldingly to the car, a lug projecting from said frame, a finger swivelly mounted on said lug, a shell telescoping over said lug and having slots adapted to engage and hold said finger from turning upon the lug, as set forth.

12. In combination with a car, a swinging frame mounted thereon, a netting carried by said frame, yielding connections between the swinging end of the frame and the car, means upon the frame for supporting a mail bag, an apron having ends passing through apertures in said frame, and means engaging said ends for holding the apron upon the frame, as set forth.

13. In combination with a car, a swinging frame mounted thereon, a netting carried by said frame, yielding connections between the swinging end of the frame and the car, means upon the frame for supporting a mail bag, a crane, a standard upon which said crane is swivelly mounted, a pivotal finger upon said crane upon which a mail bag is adapted to be mounted, and a pivotal spring-pressed frame and netting therefor mounted upon said standard, as set forth.

14. In combination with a car, a swinging frame mounted thereon, a netting carried by said frame, yielding connections between the swinging end of the frame and the car, means upon the frame for supporting a mail bag, a pivotal counter-balanced crane, a standard upon which the latter is swiveled, a pivotal finger mounted upon said crane and adapted to support a mail bag, a frame pivotally mounted upon the standard, and a netting upon said frame, as set forth.

15. In combination with a car, a swinging frame mounted thereon, a netting carried by said frame, yielding connections between the swinging end of the frame and the car, means upon the frame for supporting a mail bag, a pivotal counter-balanced crane and standard therefor, said crane being adjustably held upon the standard, means upon the crane for supporting the mail bag, and a spring-pressed frame pivotally mounted upon said standard, as set forth.

16. In combination with a car, a swinging frame mounted thereon, a netting carried by said frame, yielding connections between the swinging end of the frame and the car, means upon the frame for supporting a mail bag, a pivotal counter-balanced crane, a standard, a bracket adjustably mounted upon the standard and swivelly connected to said crane, means upon said crane for supporting a mail bag, a frame pivotally mounted upon the standard, a rod pivotally connected to the frame upon the standard, and a spring upon the rod bearing yieldingly against said frame upon the standard, as set forth.

In testimony whereof I hereunto affix my signature in the presence of two witnesses.

WYATT T. SEBREE.
